CLAIM

The ornamental design for a combined christmas tree ornament and cassette player, as shown and described.

DESCRIPTION

FIG. 1 is a front elevational view of a combined christmas tree ornament and cassette player showing my new design;

FIG. 2 is a right side elevational view thereof;

FIG. 3 is a rear elevational view thereof;

FIG. 4 is a left side elevational view thereof;

FIG. 5 is a front elevational view of a second embodiment thereof, the remaining views appearing the same as those of the first embodiment.

FIG. 1

FIG. 2

FIG. 3

FIG. 4

FIG. 5
